Dec 1746

James L. Collins, of Chicago, Ills.
Letters Patent No. 1746, dated Apr. 14, 1863.

The schedule referred to in these Letters Patent and making part of the same.

To all whom it may concern:

Be it known that I, James L. Collins, of the City of Chicago, in the County of Cook, and the State of Illinois, have invented or produced a new and original design, to be used to ornament and distinguish castings for stoves, and I do hereby declare that the following is a full and exact description of the same, the letters used referring to the accompanying drawings, or rather photographs, of said design.

I cast the stove doors or other plates with an alto relief oval shield a, in the centre which shield is ornamented by stems or fillets b, on each side with a small irregular panel i, in each, which stems or fillets terminate in buds or drops c, the leaves of which are folded over each other, and terminate in a point d. There is also a stem or fillet f, at the top and at the bottom of the shield terminating in a bud or . . . drop g, which differs from the side drops or buds in having the point e, secured by a narrow band h, and in having the body of the drop or bud surrounded by panels instead of leaves.

I do not claim all the several parts of said design when separately used or otherwise combined, but what I do claim and desire to secure by letters patent is said design as a whole, and the peculiar formation of the side buds or drops terminating in leaves folded over each other, and also the inside stem or fillet running from the buds or drops up around the centre piece to the top of the design.

Witnesses.
